UNITED STATES PATENT OFFICE.

WILMOT CASTLE, OF ROCHESTER, NEW YORK, ASSIGNOR TO WILMOT CASTLE COMPANY, OF ROCHESTER, NEW YORK, A CORPORATION OF NEW YORK.

STERILIZER.

No. 853,498.

Specification of Letters Patent.

Patented May 14, 1907.

Application filed March 16, 1905. Serial No. 250,435.

To all whom it may concern:

Be it known that I, WILMOT CASTLE, a citizen of the United States, and a resident of Rochester, in the county of Monroe and State of New York, have invented certain new and useful Improvements in Sterilizers, of which the following is a specification.

This invention relates to sterilizers, and particularly to an improved valve therefor.

o In the drawings:—Figure 1 is a longitudinal vertical section of a sterilizer provided with this invention; Fig. 2 is an inside view of the end of the valve; Figs. 3 and 4 are central vertical sections through the valve, showing the same in two different positions; and Fig. 5 is an outside view of the valve.

The base 1 is adapted to contain water, and is entirely open on top, except that around the edge is a groove or trough 2 adapted to contain water and to form a water seal around the lower edge of the sterilizer body 3. The sterilizer body has the inner chamber 4 and the outer jacket 5, whose lower edge 6 rests in the groove 2 and is sealed by water therein. The steam space 7 between the inner chamber 4 and the jacket 5 is closed at the top, as at 8. A suitable cover 9, preferably hollow, for insulating purposes, is provided for the chamber 4, and

30 is provided with a suitable outlet 10, which may be closed by a plug 11. Through the jacket 5 and the wall 12 of the inner chamber 4 are provided certain valve mechanisms, as will now be described. To the jacket 5 is

35 fastened the plate 13 having a perforation 14 therethrough. Of course, this perforation may be made through the jacket 5 itself, and the separate plate 13 merely becomes integral with the jacket wall 5. Against the surface of a plate 13 rotates the valve disk 15, having an opening 16 therein adapted to register with the perforation 14. This opening may be of any suitable length, but the preferred form shown is substantially an arc of

40 30° drawn from the point of rotation of the disk 15. Either integral with or attached to the wall 12 is another plate 17, suitably perforated, but in the present case shown as having the slot 18 extending through substantially a quarter of a circle drawn from the center of the plate 17. Against the plate 17 rotates the disk 19, suitably perforated, so as to register with the perforation 18. In the present case the disk 19 has the three perfo-

55 rations 20, Fig. 2, each one of which may register with the perforation 18. A single perforation is to be considered the equivalent of the three perforations 20. The disks 15 and 19 are fastened upon a spindle 21 having the handle 22, and rotate together. The perforations 16 and 20 are on the same side of the center of rotation and practically opposite each other, but the perforations 14 and 18, in the stationary plates or walls, are arranged on opposite sides of the center of rotation, so 60 that when the perforation or perforations 20 register with the perforation 18 to open a passage through the inner wall 12 to connect the space 7 with the interior chamber 4, the opening or perforation 14 through the outer 70 wall of the jacket 5 is closed. This position of the parts is shown in Fig. 3. But when the perforations 14 and 16 register and connect the space 7 with the outer air through the wall 5, the perforations 20 and 18 do not 75 register and the connection between the space 7 and the chamber 4 is cut off.

A deflector 23 is applied to deflect any steam that may issue through the perforations 16 and 14 away from the hand, while 80 operating the handle 22.

What I claim is:—

A sterilizer comprising a boiler having openings in one of its walls, an inner vessel within the boiler having openings in one of 85 its walls and out of line with those in the boiler, and a revoluble valve having disks spaced apart and respectively seated against the said walls of the boiler and inner vessel, and having openings to register with those of 90 said walls, so that when the valve is turned to cause the openings of one of its disks to register with those of the contiguous wall against which it is seated, those of the other disk will be out of register with those of the 95 contiguous wall against which said other disk is seated, and so that the valve may be turned to put the openings of both of its disks out of register with those of both of said walls, said valve hence enabling steam to be discharged from the boiler either into the inner vessel or the outer air and also enabling steam to be confined in the steam space of the boiler, for the purpose set forth.

WILMOT CASTLE.
